GRIPPER MECHANISM

Gustave A. Anderson, New York, N. Y., assignor to
 The International Handkerchief Mfg. Co., New
 York, N. Y., a corporation of New York

Application January 29, 1946, Serial No. 644,009

4 Claims. (Cl. 271—2.5)

1

This invention relates to mechanism for gripping the edge of a web of cloth and drawing a length of the web over an apparatus where further operations are performed on the drawn length.

The invention will be described as employed in connection with an apparatus for making handkerchief and the like such as is illustrated and described in U. S. Patent No. 2,053,257. In that patent, the web material, previously hemmed on its longitudinal edges, enters the apparatus from the side. It is gripped by grippers and approximately the required amount to form a handkerchief is drawn transversely across the apparatus. The exact length for a handkerchief is then adjusted by producing a suitable amount of slack in the web portion which has been drawn across the apparatus. The blank is then clamped along its ends and is cut off. While still held in its cut position, the first fold is given to the unhemmed or raw edges. The blank is then moved longitudinally of the apparatus, and hems are formed which are finally sewed simultaneously by two sewing machines located at the forward end of the apparatus. The handkerchief is then complete.

As a blank is moved forwardly in the apparatus, the gripping mechanism is returned to its initial position ready for gripping the edge of the web again. This return movement, in the patent structure, is effected by a spring. The drawing movement is cam controlled.

It has been found that the use of a spring to return the gripping mechanism to its initial position resulted in banging the mechanism against the frame of the apparatus with considerable force. Not only is this noisy, but such a system makes it impossible to govern accurately the depth of grip of the grippers. The depth of grip is important for it regulates the amount of turn-in, necessary for the particular kind of goods used on one side of the handkerchief, that is, the leading side as the blank is drawn from the web. The turn-in is the amount of cloth folded under first top fold of the hem.

In the patented construction to which reference has been made the springs cause a rebound of the grippers at the forward end of their stroke just as the grippers are closing on the goods, thus causing a variation in the grip and a consequent variation in the length of goods cut from the web.

It is a principal object of the present invention to provide a gripping mechanism which is not subject to these disadvantages, and which, while simple in arrangement, permits accurate adjustment of the gripping mechanism to compensate for cloth of different kinds and weaves, and which further operates quickly and efficiently.

These and other objects of the invention will become more apparent from the following de-

2

scription and claims when read in conjunction with the accompanying drawings, in which:

Fig. 1 is an end elevation showing the gripping mechanism in its gripping position;

Fig. 2 is a similar view showing the gripping mechanism at the finish of its stroke; and

Fig. 3 is a side elevation.

The mechanism is mounted on a frame which includes side members 11 and 12 which are held in spaced relationship by one or more cross-bars 13.

The reference numerals 14 and 15 represent shafts which extend across the frame from side to side and the ends of which are secured to the sides. These shafts 14 and 15 are disposed in spaced parallel relationship (Fig. 3) and they serve as guide rods for the grippers 16.

The grippers 16 are each comprised of a sleeve portion 17 which is slidably mounted on one of the shafts 14, 15, an upright arm 18 secured to or integral with the sleeve 17, and gripper jaws 19 which are normally held in closed position by springs, such as 20. One of the gripper jaw parts carries a roller 21 or the like which is adapted

in certain positions to be engaged by a cam surface, such as 22 (Fig. 2), to cause the gripper jaws to separate. The specific structure of the gripper jaws 19 is not vital to the present invention as long as they operate substantially as described.

A suitable structure for the gripper jaws is illustrated and described in U. S. Patent No. 2,053,257 to which reference has already been made. The web of cloth is gripped by the gripping jaws at the position of the jaws in Fig. 1 and the dot-dash horizontal line at the top of Figs. 1 and 2 of the drawings represents substantially the line of travel of web as it is drawn across the apparatus.

Each sleeve 17 has a pivotal connection 23 at its side with a short rod 24 which in turn is pivotally connected to a long rocker arm 25 the lower end of which is secured to a rock shaft 26 extending longitudinally of the apparatus and supported by journal blocks such as 27 carried by

the cross bars 13.

From Fig. 3 it will be seen that there are two rock arms 25 each secured at its base to the rock shaft 26. With reference to this same figure, the reference numeral 28 designates the main drive shaft of the apparatus. This shaft 28 is disposed above and to one side of the rock shaft 26 and is similarly journaled. It is adapted to be turned by any suitable means (not shown).

Secured on the main drive shaft 28 is a cam wheel 29 which is provided on one side face with a cam track 30. This cam track is engaged by a roller 31 carried on the end of one arm 32 of a double-armed lever 33 which is pivotally mounted on a stub shaft 34 disposed parallel to the rock shaft 26.

The other arm 35 of the double-armed lever 33 extends laterally and upwardly and its end 36 is pivotally connected to one end of a turnbuckle 37. The other end of the turnbuckle 37 is pivotally connected to an arm 38 rigidly secured to the rock shaft 26.

As the main drive shaft 28 is rotated the cam wheel 29 will also rotate and the roller 31 engaged in the cam track 30 will move the double armed lever 33 to pivot or rock on its shaft 34. This rocking movement is transmitted through the turnbuckle 37 to the arm 38 and consequently to the rock shaft 26. Since the long rocker arms 25 are secured to the rock shaft 26 these rocker arms, upon rocking of the rock shaft, will move from the position shown in Fig. 1 to the position shown in Fig. 2 and then back again as the cam wheel 29 makes one complete revolution. The grippers 16 will move with the rocker arms 25 and in so doing will slide on the guide shafts 14 and 15.

From Fig. 1 it will be seen that the arms 25 at their forward or initial gripping position engage stop members 39 which may advantageously be comprised of bolts secured to the frame by nuts 40. The position of the stop members 39 can thus be adjusted.

The cam track 30 has a width substantially equal to the diameter of the roller 31 except at one point, namely, that part of the cam track occupied by the roller when the parts are in the position shown in Fig. 1. At that point the cam track is enlarged. Consequently, the cam track and roller do not move the rocker arms 25 when the latter are right at the end of their forward movement (to the left in Fig. 1). The forward movement of the rocker arms 25 at the extreme end of their stroke is effected by a separate kick-over mechanism which will now be described.

Adjustably mounted rigidly on the rock shaft 26 by the set screw shown in Fig. 3 is an arcuate arm 41. Mounted rigidly on the main drive shaft 28 is an arm 42 near the end of which is a laterally extending stud 43. The arcuate arm 41 and the arm 42 are disposed in adjacent parallel planes. However, the stud 43 on arm 42 is so disposed that just as the roller 31 reaches the position in the cam track shown in Fig. 1, where the roller no longer transmits positive rocking movement to the rock shaft 26, the stud 43 on arm 42 will strike the tip end of the arcuate arm 41 and move that arm counter-clockwise thus moving the rock shaft 26 further and causing the rocker arms 25 to move into engagement with the stops 39. By means of the set screw shown in Fig. 3 on the hub of arm 41, this arm is adjustably positioned on shaft 26 so that its position can be varied angularly as the position of stop 39 is adjusted.

The advantages of employing mechanism of the type described is as follows. It has been mentioned that different types and weaves of cloth require different grips. Consequently, the limit of forward movement of the grippers 16 should be adjustable. If the cam track 30 did not have a cut out or enlarged portion at the place occupied by the roller 31 in Fig. 1, it would be apparent that the forward limit of the gripper could not be adjusted except possibly by providing a different cam wheel for each length of grip desired.

In accordance with the present invention, as will now be apparent, by providing an enlarged portion in the cam track and by providing the

kick over mechanism to move the gripper mechanism at the end of its forward stroke, the grippers move forwardly the full distance as governed by the stops 39. Because of this mechanism, adjustment of the stroke can be provided and the grippers 16 will always move the maximum amount provided by the adjustable stops. Thus the proper grip for each kind and weave of cloth may be effected.

10 I claim:

1. In a handkerchief making machines or the like in which at least one member is mounted for rocking movement, the combination of a positive stop for defining the limit of movement 15 of said member in one direction, a cam element including a cam track for imparting movement to said member, a cam follower drivably connected to said member and engaging said track, said track having an enlarged portion positioned 20 to cooperate with said follower during the final portion of movement of said member toward said stop, a first arm drivably connected to said member, and a second member movable with said cam and engaging said arm during said final 25 portion of movement of the rocking member to force said rocking member positively against said stop.

2. The mechanism of claim 1, means for adjusting said positive stop to halt movement of 30 said rocking member in the direction of the stop at variable positions, and means for adjusting the position of said arm to vary the limit of movement of the arm and rocking member by said second member.

35 3. The mechanism of claim 2 in which said first arm is arcuate in configuration, said second member comprising a second arm positioned to engage and move past the end of said first arm to bring said rocking member into engagement 40 with said stop.

4. In a handkerchief making machine or the like having a frame, a pair of parallel guide members supported by said frame, a pair of gripper members movable on said guide members between forward and rear positions for drawing lengths of material from a web, a rocking element for moving said gripper members between said positions, and an oscillatable shaft carrying said rocking element, the combination 45 of a cam member having a cam track provided at one point with an enlarged cut-away portion, a cam follower engaging said cam track, means connecting said cam follower with said shaft to oscillate the shaft upon rotation of said cam member except at the end of the forward movement of said grippers when said follower is adjacent said cut-away portion, stop means on said frame for limiting the forward movement of said grippers, a driven shaft carrying said cam member, and means carried and actuated by said driven shaft and independent of said cam to move the grippers forwardly at the extreme end of their forward movement against said stop means.

65 GUSTAVE A. ANDERSON.
